(57) **CLAIM**

The ornamental design for a probe head for robotic therapy unit, as shown and described.

DESCRIPTION

FIG. 1 is a perspective view of a probe head for robotic therapy unit according to the present design;

FIG. 2 is a front view of the present design, a corresponding rear view being a mirror image thereof;

FIG. 3 is a right side view of the present design, a corresponding left side view being a mirror image thereof;

FIG. 4 is a top view of the present design;

FIG. 5 is a bottom view of the present design;

FIG. 6 is an underside looking perspective of the present design; and,

FIG. 7 is a second underside looking and one hundred and eighty degree rotated perspective of the present design shown in FIG. 6.

The broken lines shown in the drawings are included for the purpose of illustrating portions of the article that form no part of the claimed design.

1 Claim, 4 Drawing Sheets
